[57] CLAIM

The ornamental design for a golf club head, as shown and described.

DESCRIPTION

FIG. 1 is a rear perspective view of a golf club head embodying our new design, with a golf club shaft and grip shown in broken lines for illustrative purposes only;

FIG. 2 is a rear elevation view of the golf club head shown in FIG. 1;

FIG. 3 is a front elevation of the golf club head shown in FIG. 1;

FIG. 4 is a toe-end elevation of the golf club head shown in FIG. 1;

FIG. 5 is a top plan view of the golf club head shown in FIG. 1;

FIG. 6 is a sectional view of the golf club head shown in FIG. 2 taken along lines 6—6 thereof;

FIG. 7 is another sectional view of the golf club head shown in FIG. 2 but viewed along lines 7—7 thereof;

FIG. 8 is a generally horizontal sectional view of the golf club head shown in FIG. 2 viewed along lines 8—8 thereof;

FIG. 9 is a rear elevation view of another embodiment of our new design of a golf club head;

FIG. 10 is a sectional view of the golf club head shown in FIG. 9 viewed along lines 10—10 thereof;

FIG. 11 is another sectional view of the club head shown in FIG. 9 viewed along lines 11—11 thereof; and,

FIG. 12 is a generally horizontal sectional view of the golf club head shown in FIG. 9 as viewed along lines 12—12 thereof.
